UNITED STATES PATENT OFFICE.

LOUIE F. HOFFMAN AND WALTER H. WAKEFIELD, OF WORCESTER, MASSACHUSETTS,
ASSIGNORS TO CROMPTON & KNOWLES LOOM WORKS, OF WORCESTER, MASSA-
CHUSETTS, A CORPORATION OF MASSACHUSETTS.

NEEDLE FEELER FOR LOOMS.

Application filed January 2, 1925. Serial No. 28.

This invention relates to weft detectors for looms and more particularly to the type cooperating with a specially formed bobbin and arranged to be given varying degrees 5 of sensitiveness depending upon which one of a plurality of shuttles is active.

When weaving certain types of fabrics which require very fine and also very coarse yarn in the weft it is sometimes found that 10 a weft detector having a fixed adjustment is not suitable for use on both kinds of weft inasmuch as a setting which would leave a permissible amount of waste when indicating with large yarn would leave too much 15 waste when indicating exhaustion of the fine weft.

It is the principal object of our present invention to provide a weft detector of the type specified wherein the pressure of the 20 parts cooperating with the bobbin can be varied in timed relation with the active shuttle.

It is a further object of our invention to provide a weft detector which shall have a 25 sensitiveness variable under control of the shifting shuttles and also permitting excessive forward motion of the detector when the latter is engaged by a misplaced shuttle.

With these and other objects in view 30 which will appear as the description proceeds, our invention resides in the combination and arrangement of parts hereinafter described and set forth in the claims.

In the accompanying drawings wherein 35 we have shown one form of our invention, Fig. 1 is a front elevation of a loom having our invention applied thereto.

Fig. 2 is a vertical section on line 2-2 of Fig. 1 looking in the direction of the arrows, 40 Fig. 3 is an enlarged detail horizontal section taken on line 3-3 of Fig. 2.

Fig. 4 is an enlarged end elevation of the detector looking in the direction of arrow 4, Fig. 1, the lay, shuttle, and bobbin being 45 shown in section,

Fig. 5 is a front elevation of the structure shown in Fig. 4,

Fig. 6 is an enlarged view of certain parts shown in Fig. 4 in a different position, and 50 Fig. 7 is a vertical section taken on line

7-7 of Fig. 6.

Referring more particularly to Figs. 4, 5, and 6 it will be seen that we have provided a stand 10 secured in any approved manner

to the loom frame 11 and having bolted 55 thereto an upstanding plate 12 having an overhanging arm 13. Said plate is provided with a rib 14 which fits in a notch 15 formed in the lower portion of a carrier 16. A bolt 17 passing through the plate 12 and carrier 16 has a head on the rear end thereof to engage the plate and has a nut 18 by means of which a spring 19 on said bolt may be adjusted. Said spring 19 yieldingly positions the carrier 16 and permits the same to move 60 65 forwardly when engaged by an abnormally placed bobbin or part of the loom.

The carrier is provided with a rearwardly extending guide 20 and an upper guide 21 spaced therefrom, said guides being drilled 70 as indicated in Fig. 5 to receive a plurality of detectors 22 each of which has a lower leg, the rear end of which extends beyond the end of the guide 20, and a shorter upper leg which protrudes slightly beyond the upper 75 face of the carrier 16.

Associated with the stand 10 is a bearing 23 in which is slidably mounted a block 24 to the upper end of which is pivoted at the central portion thereof as at 25 a lever 26. 80 The forward end of said lever extends over the upper ends of the detectors 22 as indicated in Fig. 5 while the other end is connected by means of link 27 to a weft replenishing mechanism, preferably of the form 85 shown in Patent No. 1,030,748. The block 24 receives a regular reciprocating motion and when all of the detectors 22 are removed from under the lever 26 the latter will move 90 downwardly without depressing the link 27 but when one of the detectors is under said lever the downward motion of the block 24 will depress the link 27 to give an indication of substantial weft exhaustion.

Each of the detectors 22 has a vertical portion 28 and there is provided a plurality of weights W described hereinafter and having portions thereof in contact with the vertical parts of the detector wires to hold the latter rearwardly in yielding position. The matter thus far described is substantially the same as shown in application Serial No. 643,211 and forms no part of our present invention.

In carrying out our invention we provide 105 means for varying the pressure of the weights W against the detector wires so that under certain conditions, as when very fine

yarn is being woven, the pressure will be light and under other conditions, as when relatively coarse yarn is being woven, the pressure will be greater. As shown in Figs. 5 and 7 the guide 20 has extending therefrom a hub 50 through which extends the reduced bearing 51 of an eccentric 52. Said eccentric is provided with a pair of grooves 53 which receive the depending open bearings 54 and 55, respectively, of a brace 56. The lower end of open bearing 55 is provided with a finger 57 which extends behind the vertical portions of the detectors 22 and an offset 58 which is positioned to be engaged by a stud 59 extending from a portion of the transferrer arm indicated at 60.

The weights W are loosely mounted on eccentric 52 and are restrained against end motion by the depending open bearings 54 and 55, each weight having a pressure finger 61 to engage the vertical portion 28 of the corresponding detector 22.

The bearing 51 is extended beyond hub 50 and has secured thereto a pinion 62 which moves with the eccentric 52. A stud 63 extending from the guide 20 closely adjacent the notch 15 has pivoted thereon a rack lever 64 the upper end of which is provided with rack teeth 65 which mesh with the teeth of the pinion 62. The lower end of the rack lever is provided with an arm 66 by means of which the lever is oscillated on the stud 63.

The mechanism for moving the lever 64 is shown in Figs. 1, 2, and 3, where it will be seen that a rocker shaft 67 having secured thereto a picker foot 68 is rotatably mounted on the loom frame 11. A box rod 69 of any approved construction carries at the upper end thereof a multiple of boxes, four boxes being shown in the present instance. Secured to the box rod is an arm 70 the upper end of which is connected as at 71 to a slide 72 the lower end of which is guided in a slide bearing 73, said slide bar being held in the bearing by plates 74. The slide bearing has a support 75 which is secured to the picker foot 68 so that the box rod, slide bar, and slide bearing move as a unit about the rocker shaft 67.

The mechanism for determining when the pressure of the detector wires should be reduced or increased comprises a lever 76 pivoted as at 77 to the picker foot and having a roll 78 which is normally held toward the slide block 72 by means of spring 79 interposed between said lever 76 and the picker foot. Removably secured to the slide block are tappets 80 which are held thereto by screws 81, said tappets being the same height when it is desired to have but two degrees of pressure or being of variable heights when it is desired to have more degrees of pressure. Attached to the lower end of the lever 76 is a flexible connector 82 which extends across the loom and around a sheave 83 and

has the upper end thereof connected to lever 64. The spring 79 is relatively heavy and holds the roll 78 against either the tappets or the slide bar and a relatively lighter spring 84 is provided between the hub 85 and the lever 64. Spring 84 normally tends to move said lever 64 to the right as shown in Fig. 4.

As shown in Figs. 1 and 5 the detector is set to detect for heavy yarn, and for the purposes of illustration it is assumed that the first and third boxes receive shuttles with heavy yarn and that boxes two and four receive shuttles supplied with fine yarn. The tappets 80 correspond to the fine yarn and that part of the bar 72 against which the face 78 may press corresponds to the coarse yarn. The detector cooperates with a specially formed bobbin having holes drilled therein in accordance with either Patent No. 1,220,685 or Patent No. 1,337,706 and whenever the yarn is sufficiently depleted to permit one of the wires 22 under the action of its weight to enter one of the holes, the lever 26 will be held up as previously described to give an indication of weft exhaustion.

When the active shuttle changes so that the weaving of coarse weft ceases and a shuttle carrying fine yarn becomes active, the box rod 69 will be moved so that the face 78 will rest on one of the tappets 80 which will produce a corresponding right hand motion of the lever 64 to permit the rack teeth 65 to give the pinion 62 half a rotation. The eccentric 52 will thereby be thrown rearwardly and the centers of the weights W will also be moved rearwardly to bring the point of support of said weights more nearly in vertical alignment with their centers of gravity. The pressure of the fingers 61 against the wires will therefore be reduced and the layer of yarn on the bobbin can become thinner before being penetrated by one of the detectors 22 than is the case with the coarser yarn.

From the foregoing it will be seen that we have provided a weft detector for use with a specially formed bobbin provided with means for varying the pressure of said detector against the bobbin so that when coarse yarn is being woven a relatively high pressure of the detector is maintained but when finer yarn is being woven a relatively lower pressure can be used. It will also be seen that we have provided means for varying the detector in its degrees of sensitivity by means which permit the use of two or more shuttles of one character of filling, the tappets being changeable from one position to another to permit the shuttles to occupy any desired position in the boxes. It will be further noted that the guide for the detector when engaged by a misplaced part will move forwardly and carry the rack and pinion therewith to keep said parts in

mesh. Furthermore, since the axis of stud 63 is substantially in line with the rib 14 the spring 84 exerts no force tending to turn the guide 20.

Having thus described our invention it will be apparent that changes and modifications may be made therein by those skilled in the art without departing from the spirit and scope of the invention and we do not wish to be limited to the details herein disclosed, but what we claim is:

1. In a loom having a plurality of shuttles, shifting shuttle boxes to move any one of the shuttles to active position, a detector to cooperate with the shuttle which is active, and means coordinated with the shuttle boxes and dependent upon which shuttle is active to vary the pressure of the detector against the surface to be detected.

2. In combination, a weft detector having a plurality of elements to cooperate with a specially formed bobbin, a plurality of shuttles each provided with a specially formed bobbin and capable of becoming active one at a time, shifting shuttle boxes to determine which shuttle shall be active and means acting in timed relation with the shuttle boxes and dependent upon which shuttle is active to vary the pressure of said elements against the bobbin.

3. In a loom, shifting shuttle boxes, a plurality of shuttles for the boxes each movable by the boxes to active position and each provided with a specially formed bobbin, a weft detector to cooperate with the bobbin of the active shuttle to detect for weft exhaustion, said detector being capable of exerting varying degrees of pressure on the bobbins, and means operating in timed relation with the shuttle boxes to vary the pressure exerted on the bobbin in the active shuttle by the detector.

4. In a loom having a plurality of shifting shuttle boxes, and a plurality of shuttles movable to active position one at a time and each provided with a bobbin of special construction, a weft detector having elements to enter portions of the specially formed bobbins to indicate weft exhaustion, and means under control of the shuttle boxes to vary the force acting to move the elements into the specially formed parts of the bobbin.

5. In a loom, shifting shuttle boxes, in combination, a detector having a plurality of detecting elements, a plurality of shuttles for the boxes each of which may become active and each of which carries a bobbin having a portion to receive one of the detecting elements at indication of weft exhaustion, and yielding means acting on the detecting elements tending to move them into the portion of the bobbin arranged to receive them, said means being operatively connected to the boxes and movable thereby

to vary the degree of pressure exerted on the bobbin of the active shuttle, the pressure being dependent upon which shuttle is active.

6. In a loom, in combination, shifting shuttle boxes carrying shuttles any one of which may become active each shuttle having a bobbin therein, a weft detector to cooperate with each shuttle when active and dependent for its operation upon the degree of pressure exerted thereby on the bobbin of the active shuttle, means moving with the shuttle boxes and defining surfaces of different heights, and means cooperating with said first named means and operatively connected with the detector to vary the degree of pressure exerted thereby on the bobbin of the active shuttle.

7. In a loom, in combination, shifting shuttle boxes, shuttles for the boxes each having a bobbin therein, a plurality of surfaces of different heights movable with said shuttle boxes, a weft detector to cooperate with the active shuttle and dependent for its operation upon the degree of pressure exerted thereby on the bobbin of the active shuttle, and means cooperating with said surfaces of different heights to vary the degree of pressure exerted by the detector on the bobbin to be detected.

8. In a loom, in combination, shifting shuttle boxes, shuttles for the boxes each having a bobbin therein, means defining a plurality of surfaces of different heights movable with said shuttle boxes, a lever to cooperate with each of said surfaces of different heights, a detector dependent for its operation upon the degree of pressure exerted thereby on the bobbin of the active shuttle, and means controlled by said lever to vary the pressure of said detector against the bobbin of the active shuttle as said lever ceases to cooperate with one of said surfaces and cooperates with another of said surfaces of different height.

9. In a loom, in combination, a plurality of shifting shuttle boxes carrying shuttles each having a bobbin and each of which may become active, a lever, a plurality of stops of different heights movable with the shifting shuttle boxes and effective to give said lever different angular positions, a weft detector, dependent for its operation upon the degree of pressure exerted thereby on the bobbin of the active shuttle, and means to vary the pressure of said detector on the bobbin of the active shuttle as the lever changes its angular position.

10. In a loom, in combination, shifting shuttle boxes, a plurality of shuttles each of which may become active, a plurality of stops of different heights movable with said shifting shuttle boxes, a device cooperating with said stops to assume different positions, a detector to cooperate with the

- active shuttle and dependent for its operation upon the degree of pressure exerted thereby on the bobbin of the active shuttle, and means to vary the pressure of said detector on the bobbin of the active shuttle as said device changes its position.
11. In a weft detector for looms having a shuttle with a specially formed bobbin therein, said detector comprising a plurality of individually movable detecting elements to cooperate with the bobbin and dependent for indicating movement upon the pressure exerted by the elements against the bobbin, weighted means cooperating with the elements and determining the pressure exerted by said elements on the bobbin, and a support for said weights movable relatively to the elements to vary the pressure exerted thereby on the elements.

12. In a weft detector for looms having a shuttle with a specially formed bobbin therein, said detector comprising a plurality of individually movable detecting elements dependent for indicating movement upon the pressure exerted by the elements against the bobbin, a freely movable weight for each element, a pivotal support for each weight, the weights determining the pressure exerted by the elements on the bobbin, and means to shift the position of the pivotal support for the weights to vary the pressure exerted thereby against the elements.

In testimony whereof we have hereunto affixed our signatures.

LOUIE F. HOFFMAN
WALTER H. WAKEFIELD.
